UNITED STATES PATENT OFFICE

FRANK SCHAUMAN AND BROR MAX SCHAUMAN, OF NEW YORK, N. Y., ASSIGNORS TO
AUTOMATIC ANCHOR-CONTROL CORPORATION, OF NEW YORK, N. Y., A CORPORATION
OF NEW YORK

ANCHOR DAVIT

Application filed October 7, 1927. Serial No. 224,565.

This invention relates to anchor davits, and has for its general object and purpose to provide a davit construction which consists of relatively few parts compactly arranged and occupying relatively little space on the deck of the vessel and embodying automatically operating means for fixedly securing the anchor in place against possible shifting in the pitching or rolling of the vessel in heavy seas.

It is another object of the invention to provide a davit construction whereby the anchor may be easily and quickly cast or weighed and which embodies a plurality of slidable and pivotally movable parts and means automatically operating when the anchor is weighed to position said parts in vertically superimposed relation to each other.

More specifically, the invention in one embodiment thereof, includes a sliding carriage mounted on the deck of the vessel and a davit member pivotally supported at one of its ends upon said carriage, together with a pivoted anchor lifting and supporting member adapted to be projected beyond the bow of the vessel at the end of movement of the carriage in one direction whereby the weight of the anchor will act to pivotally move the davit to an extended position relative to the carriage to properly support and guide the anchor chain in the casting of the anchor.

With the above and other objects in view, the invention consists in the improved anchor davit, and in the form, construction and relative arrangement of the several parts thereof as will be hereinafter more fully described, illustrated in the accompanying drawings, and subsequently incorporated in the subjoined claims.

In the drawings, wherein we have illustrated one simple and practical embodiment of the invention, and in which similar reference characters designate corresponding parts throughout the several views, —

Figure 1 is a top plan view showing the pivoted davit member in its extended position relative to the sliding carriage;

Fig. 2 is a side elevation partly in section;

Fig. 3 is a side elevation showing the davit member and associated parts in superposed position upon the deck of the vessel, but with the carriage at the end of its outward movement in position for the casting of the anchor;

Fig. 4 is a detail transverse section taken on the line 4—4 of Fig. 1, and

Fig. 5 is a similar sectional view taken on the line 5—5 of Fig. 1.

Referring in detail to the drawings, 5 designates an elongated guide bed which is adapted to be suitably secured upon the deck of the vessel. This guide bed is of channel shaped form in cross section having the parallel longitudinal side walls 6 to the upper edges of which angle bars 7 are secured with one of their flanges projecting inwardly from the wall 6 as shown in Fig. 4 of the drawings. To the corresponding ends of the side walls 6 of the guide bed longitudinally extending upwardly projecting arms 8 are fixed, each of said arms terminating at its upper end in a stop lug 9.

The carriage 10 supported upon the guide bed 5 is also of channel shaped form in cross section, the side walls or flanges 11 thereof being provided on their outer sides adjacent their rear ends with the rollers 12, which track or ride upon the under sides of the horizontal flanges of the angle bars 7. Additional rollers 13 are also mounted upon the outer sides of the flanges 11 adjacent their forward ends and track upon the base of the guide bed 5.

The side flanges 11 of the carriage 10 at 85 their forward ends are formed with upwardly projecting arms 14 in which a transverse rod or shaft 15 is fixed. The ends of this shaft are adapted to engage in bearing seats on the lugs 9 to limit the forward movement 90

of the carriage in the casting of the anchor, as will be subsequently explained in detail.

Upon the rear end of the carriage in a suitable bearing bracket 16, a guide sheave 17 for the anchor chain C is journalled. To this rear end of the carriage on the under side thereof one end of a rope or cable 18 is suitably attached, said cable extending around a guide sheave 19 rotatably mounted upon the base of the bed 5 between the same and the carriage 10. The other end of this cable is connected to a suitable drum or windlass (not shown) upon which the cable is wound, and which is adapted to be connected to a suitable operating motor to move the carriage and the parts mounted thereon in an outward direction relative to the guide bed and to the position shown in Fig. 3 of the drawings.

Upon the rod or shaft 15 the davit member 20 is mounted at one of its ends for pivotal movement, said davit having an anchor chain guiding sheave 21 journalled in its other end and a transversely positioned rod 22 fixed to said davit member inwardly of said sheave and terminating at its ends in the heads 23. As shown, the davit member includes longitudinally converging side bars 24 rigidly connected with each other by the reinforced channel shaped plate 25. Said davit member also includes the additional parallel members 26 extending beneath the plate 25 and projecting rearwardly from said plate and having their rear ends loosely engaged upon the pin or rod 15.

Upon the rod 15 a pinion 28 is secured and is engaged by the gear 29 fixed on a shaft 30 journalled in the spaced members 26 of the davit member. This gear in turn meshes with a gear 31 secured upon the shaft 32 which is journalled in the spaced bars 26. To the opposite ends of this shaft 32, the extremities of an elongated U-shaped bar 33 are rigidly connected the end portions thereof having inwardly extending flanges 27. This bar in side elevation is of substantially Z-shaped form having an intermediate angular bend 34 in each of the side parts thereof and between which the davit member is adapted to project so that the intermediate portion of said U-shaped bar will be positioned above the outer end of the extended davit member as shown in Fig. 2 of the drawings. By the provision of the gearing just described, the U-shaped bar 33 will at all times be maintained in the same horizontal position relative to the davit carriage during the pivotal movements of said davit member as will be readily seen from a comparison of Figs. 2 and 3 of the drawings.

Spaced bars 35 are also pivotally mounted adjacent one of their ends upon the fixed rod 15, said end portions of the bars in spaced relation to said rod being provided with shoulders indicated at 36 which are adapted

to be engaged by the studs 37 provided on the members 24 of the davit member. Between the other ends of these bars 35 a guide sheave 38 for the anchor chain, is journalled, said chain extending from said sheave over the sheave 21 in the end of the davit member and being connected to a rod 40 on the end of a link 39 which is pivotally connected to the end of the anchor shaft 41 as shown in Fig. 3 of the drawings. The other end of this shaft has a suitable connection with the anchor head 42. The ends of the rod 40 are provided with rectangular projections which when the anchor shaft is in a vertical position, are adapted to pass through the restricted entrances of the notches or seats 43 provided in the ends of the spaced parts 24 of the davit member so that when the anchor is lifted and disposed in the horizontal position shown in Fig. 3, the rod 40 will be locked in connection with the end of the davit member.

Upon the fixed rod or shaft 15 of the carriage 10, an anchor head lifting and supporting member 44 is pivotally mounted, said member consisting of a plate having spaced arms fixed to one side thereof and pivoted on the rod 15 and provided with extensions or projections 45 located on the opposite side of said rod with respect to the anchor lifting plate. These extensions 45 of the arms are adapted for engagement by the pins or studs 46 fixed to the outer sides of the parts 24 of the davit member so that as the davit member is moved from the position shown in Fig. 2 to the position of Fig. 3, the member 44 will also be pivotally moved on the rod 15 in an upward direction as the anchor shaft and head swing inwardly towards the davit member so that the anchor head is received upon the supporting plate or member 44 and sustained thereby as seen in Fig. 3 of the drawings.

The horizontal flanges of the angle bars 7 on the upper edges of the side walls of the guide bed 5 are provided with oppositely located notches 47 opening upon the inner edges of said flanges. With these notches the upper open ends of the vertical slots 48 in the opposite side flanges 11 of the carriage 10 are adapted to register when the carriage reaches the limit of its forward movement on the guide bed as shown in Fig. 1 of the drawings. These slots 48 receive the opposite ends of the rod 22 carried by the davit member, the enlarged heads 23 of said rod passing through the notches 47 and below the plane of the flanges of the angle bars 7.

It will be understood that normally when the anchor is not in use, the carriage 10 with the anchor davit and its associated parts together with the anchor are positioned rearwardly of the position illustrated in Fig. 3 with respect to the guide bed 5 by the wind-

ing of the anchor chain upon the windlass, and in such normal position the horizontally extending anchor head supporting member 44 is located above the forward end of the 5 guide bed so that none of the parts project beyond the side of the ship or vessel. It will be evident that since in this normal position the heads 23 on the end of the rod 22 are located beneath the flanges of the angle bars 7, the anchor davit is securely locked against an upward pivotal movement upon the carriage. As the end of the anchor shaft is also locked to the davit member, and the member 33 extends forwardly over and in engagement with 10 the anchor head 42, the anchor and the davit are securely held against any possibility of shifting movement relative to each other or with relation to the deck of the vessel when the vessel is subjected to the buffeting of 15 heavy seas.

In the casting of the anchor, the rope or cable 18 is wound upon the drum or windlass, it being understood that the wildcat of the anchor chain windlass is disconnected from 20 the operating motor so that the anchor chain may be freely paid out as the carriage 10 moves outwardly upon the guide bed 5. This outward movement of the carriage is limited by the ends of the rod or shaft 15 engaging 25 the lugs 9, at which time the anchor head 42 and the supporting member 44 therefor will be positioned beyond the side of the vessel and the rod 22 on the davit member will be in line with the notches 27 in the flanges of 30 the angle bars 7. Under the weight of the anchor head 42, the member 44 will swing downwardly and the extensions or projections 45 thereon bearing against the lugs or studs 46 on the davit member will swing said 35 davit member upwardly past the vertical position after which the swinging movement of the davit member continues by gravity until it reaches the extended horizontal position shown in Fig. 2 of the drawings, such movement of the davit member to the extended position being limited by contact of the inner 40 ends of the parts 24 thereof against the end of the carriage 10. In this downward swinging movement of the davit member to the extended position, the studs or lugs 37 thereon strike upon the shoulders 36 of the bars 35 and swing said bars upwardly to the vertical position shown in Fig. 2 of the drawings thereby properly supporting and guiding the 45 anchor chain which moves freely over the sheave 38 in the continued downward movement of the anchor, it being understood that as the davit member reaches its extended horizontal position, the locking connection between said member and the anchor shaft is 50 released by the rectangular ends of the pin 40 coming into registration with the restricted entrances of the notches or seats 43. Also, it will be obvious that in this swinging movement of the anchor to the extended position,

the gear 29 mounted thereon will track around the fixed pinion 28, the rotation of said gear being transmitted through the pinion 31 to shaft 32 whereby the member 33 is at all times maintained in the same horizontal position substantially in parallel relation to the carriage 10. It will thus be apparent that by means of our present improvements, the ship's anchor can be quickly cast or weighed, and in the latter operation, the several parts of the davit mechanism automatically move into compact relation with each other upon the carriage 10 and together with the anchor are individually locked and securely held against movement relative to each other or to the carriage. When the carriage is drawn rearwardly or to the limit of its inward movement, the davit mechanism occupies but little of the deck space and does not detract from the neat appearance of the vessel. Thus, it will be appreciated that such an anchor casting and weighing mechanism is capable of very advantageous use upon pleasure yachts and other small vessels as well as large steamers.

From the foregoing description considered in connection with the accompanying drawings, the several novel features of our improved anchor davit and the construction and operation thereof will be clearly understood. It will be seen that the various elements are of substantial and durable construction so that the mechanism is not liable to get out of order or require frequent repair. Therefore, the maintenance cost of such a device will be comparatively small.

We have disclosed herein an embodiment of our present improvements which we believe to be entirely satisfactory and practical for the purpose in view, nevertheless it is to be understood that the several essential parts of the improved anchor davit might be constructed in various other alternative forms, and it is accordingly to be understood that in the further development of the device we reserve the privilege of resorting to all such legitimate changes therein as may be fairly embodied within the spirit and scope of the invention as claimed.

We claim:

1. Anchor davit mechanism including an anchor carriage, a davit member pivoted at one of its ends and having an anchor chain guide at its other end, a pivotally mounted anchor head receiving and supporting member adapted to be moved under the weight of the anchor in the casting thereof, and said supporting member and the davit member having co-acting means whereby in the movement of said supporting member, said davit member is pivotally moved to its anchor casting position.

2. Anchor davit mechanism including an anchor carriage, a davit member pivotally mounted at one of its ends upon the carriage

and having an anchor chain guide at its other end, and a pivotally mounted anchor head receiving and supporting member, said supporting member and the davit member having coacting means operating in the pivotal movement of the supporting member under the weight of the anchor to pivotally move the davit member from a superimposed position on the carriage past a perpendicular position whereby the davit member may drop by gravity to its anchor casting position in extended relation to the carriage.

3. Anchor davit mechanism including a carriage, a davit member pivotally mounted at one of its ends upon the carriage and having an anchor chain guide at its other end, means locking the davit member in superimposed relation upon the carriage during movement of the latter but releasing said member for pivotal movement at the end of the carriage movement in one direction, and a pivotally mounted anchor supporting member, said supporting member and the davit member having coacting means whereby upon the release of the davit member and the pivotal movement of the supporting member under the weight of the anchor, said davit member is moved past a perpendicular position to drop by gravity to its anchor casting position in extended relation to the carriage.

4. Anchor davit mechanism including a carriage, a davit member pivotally mounted at one of its ends upon the carriage and having an anchor chain guide at its other end, means locking the davit member in superimposed relation upon the carriage during movement of the latter but releasing said member for pivotal movement at the end of the carriage movement in one direction, and an anchor head receiving and supporting member pivotally mounted on the carriage, said supporting member and the davit member having coacting means preventing pivotal movement of the supporting member while the davit member is locked to the carriage and operating upon the release of the davit member in the movement of the supporting member under the weight of the anchor head to pivotally move the davit member past a perpendicular position and permit the same to drop by gravity to its anchor casting position in extended relation to the carriage.

5. Anchor davit mechanism including a carriage, a davit member pivotally mounted at one of its ends upon the carriage and having an anchor chain guide at its other end, means locking the davit member in superimposed relation upon the carriage during movement of the latter but releasing said member for pivotal movement at the end of the carriage movement in one direction, an anchor head receiving and supporting member pivotally mounted on the carriage and movable under the weight thereof in the casting of the anchor, said member and the davit

member having coacting means whereby the davit member is pivotally moved past a perpendicular position to drop by gravity to an extended anchor casting position with respect to the carriage, means pivotally connected with the davit member to engage and hold the anchor head upon said supporting member when the anchor is weighed, and means for maintaining said holding means in a constant position relative to its pivotal axis during the pivotal movements of the davit member.

6. Anchor davit mechanism including a carriage, a davit member pivotally mounted at one of its ends upon the carriage and having an anchor chain guide at its other end, means locking the davit member in superimposed relation upon the carriage during movement of the latter but releasing said member for pivotal movement at the end of the carriage movement in one direction, an anchor head receiving and supporting member pivotally mounted on the carriage and movable under the weight thereof in the casting of the anchor, said member and the davit member having coacting means whereby the davit member is pivotally moved past a perpendicular position to drop by gravity to an extended anchor casting position with respect to the carriage, means pivotally connected with the davit member to engage and hold the anchor head upon said supporting member when the anchor is weighed, means for maintaining said holding means in a constant position relative to its pivotal axis during the pivotal movements of the davit member, an additional anchor chain support and guide pivotally mounted on the carriage, and means for moving the same from a superimposed position in relation to the carriage to a perpendicular chain supporting position in the pivotal movement of the davit member to its extended position with relation to the carriage.

7. Anchor davit mechanism including a carriage, a davit member pivotally mounted at one of its ends upon the carriage and having an anchor chain guide at its other end, an anchor head receiving and supporting member mounted on the pivot of the davit member for movement relative thereto, an additional anchor chain guide and support pivotally mounted on the pivot of said davit member, said carriage being moved in one direction under the pull of the anchor chain, means for moving the carriage in the opposite direction, means for locking the davit member in horizontal superimposed relation upon the carriage during the movements of the latter but releasing said member for pivotal movement at the end of the carriage movement in one direction, coacting means on said supporting member and the davit member operating in the movement of the supporting member under the weight of the anchor when

the davit member is released to move the latter past a perpendicular position and permit the same to drop by gravity to an extended position in relation to the carriage, and means on the davit member coacting with said anchor chain support in the latter movement of the davit member to move said support to a perpendicular position relative to the davit member.

10 In testimony that we claim the foregoing as our invention, we have signed our names hereto.

FRANK SCHAUMAN.
BROR MAX SCHAUMAN.
